PAVEMENT JOINT

Alan E. Brickman, Monongahela, Pa., assignor to
 The American Steel and Wire Company of New
 Jersey, a corporation of New Jersey

Application November 19, 1940, Serial No. 366,307

5 Claims. (Cl. 94—18)

This invention relates to pavement joints, and more particularly to those which are used in paving to compensate for the expansion and contraction thereof.

Pavement joints of the type described are finding extremely wide usage, but are subject to several deleterious factors and consequently frequently present difficulties.

For a satisfactory pavement joint of the type to which the present invention appertains, attention is directed to Patent No. 2,201,823, dated May 21, 1940.

It is an object of the present invention to provide a joint for paving which overcomes disadvantages of the devices of the prior art.

Another object is to effect better surface alignment of one pavement slab with the adjacent slab in the pavement's cycles of expansion, contraction, warping, internal stress, subgrade variations, and wheel load.

A further object is the provision of a device of the class described which is relatively easy and inexpensive to manufacture and install, and one which is at the same time very efficient and durable in service.

The foregoing and other objects will become apparent after referring to the drawings, in which:

Figure 1 is a side elevation of the device of the present invention showing parts thereof in section;

Figure 2 is a plan;

Figure 3 is a view similar to Figure 1 but showing the relative positions of the parts of the device of the present invention when the adjacent paving slabs have moved closer together;

Figure 4 is an end elevation;

Figure 5 is a perspective of a detail;

Figure 6 is a perspective of another detail.

Referring more particularly to the drawings, the numeral 1 generally designates the base member of the pavement joint of the present invention. More specifically, the base member 1 takes the form of a malleable iron or steel member having oppositely disposed extensions 2. Integrally formed on the base member 1 and in parallelism one with respect to the other there is carried a pair of vertical uprights 3 which provide reversely curved portions 4 extending toward each other and terminating in elongated complementary vertical extensions 5. As shown more clearly in Figures 1 and 3, the adjacent faces of the uprights 3 immediately below the reversely curved portions 4 provide rod-receiving recesses 6, the function of which will be described

hereinafter. The upper ends of the complementary vertical extensions 5 carry oppositely extending horizontal portions 8 which are adapted to be imbedded in the adjacently disposed paving slabs which the joint of the invention is adapted to connect. At the upright ends of the complementary vertical extensions 5, and on opposed adjacent surfaces thereof, there are provided rod-receiving recesses 9 which are similar to the rod-receiving recesses 6.

On each of the remote sides of the vertical uprights 3, reversely curved portions 4 and complementary vertical extensions 5, there is carried a compressible element 11 which is provided with a cut-out portion 12 for straddling the adjacent extensions 2 of the base member. These compressible elements 11 also provide reversely curved portions 13 for conformity with the reversely curved portions 4 of the uprights 3, and tapered upper portions 14, one face of which contacts for a substantial distance the adjacent surfaces of the vertical extensions 5.

Through each of the rod-receiving recesses 6 and 9 there is disposed to extend a rod 18, each rod 18 being held in position by a U-shaped wire clip 20 having at each of its ends a curved portion 21 for embracing the said rod. The U-shaped wire clips 20, for embracing the lower of the rods 18, are disposed around the compressible elements 11 adjacent the bases of the tapered portions 14 thereof.

The wire clips 20 for the upper rods 18 are similar in shape to those previously described and indicated by the same number, but in lieu of embracing a compressible element in the manner previously described, are adapted to embrace raised portions 24 which are integrally formed on the upper surfaces of the horizontal extensions 8 which are carried by the complementary vertical extensions 5 of the base member 1.

Extending between the adjacent faces of the complementary vertical extensions 5 of a series of aligned base members 1 is a compressible element 26. In installation, a single compressible element 26 is disposed to extend entirely across the roadway, and embodies cut-out portions 27 for straddling the mid-portions of the series of aligned and suitably spaced base members 1.

In order to initially secure the joint assemblies on a prepared subgrade so as to span the distance between the pavement lane forms, the remote ends of the extensions 2 of the base member 1 carry compressible elements 30 having on their inner ends U-shaped staples 31, the legs of the latter extending through the compressible ele-

ments 30 and being bent at right angles, as shown at 32. Adjacent the remote ends of the extensions 2, each is provided with a vertical aperture 35 which receives a spike 37 which is driven into the subgrade. The spikes 37 therefore serve the dual function of initially securing the joint assemblies and holding the compressible elements 30 in position.

A removable strip (not shown) is disposed across the top of the compressible element 26 and the concrete is poured. After the concrete has set, the strip is removed and a mastic seal 38 is poured into the void formed by the removable strip.

It will be understood by those skilled in the art that the rods 18 preferably extend throughout the width of the pavement in the manner of the compressible element 26. The compressible element 26 is generally composed of asphalt saturated felt, rubber, cork board or corn stalk composition, and is stiffened longitudinally to withstand installation handling and the flow of the poured concrete by the rods 18. These rods 18 also secure the plurality of base members 1 (which, for example, may be five in number extending across the pavement) in unit assembly with the compressible element 26.

After the pavement joint has been installed and the concrete or other paving material poured, the construction and arrangement is such that with a rise in temperature the adjacent slabs expand so as to move on the subgrade. This movement is unrestricted as the compressible element 26 and mastic seal 38 are compressed. Similarly, the compressible elements 30 at the remote ends of the extensions 22 of the base member 1 are compressed. The compressible element 11 on the remote sides of the vertical extensions 5 also provide for unrestricted movement of the adjoining portions of the pavement slabs, where otherwise the latter would tend to shear the vertical uprights from the base member 1. The compressible elements 11 and the compressible element 26 permit the complementary vertical extensions 5 to bend or flex.

The expansion of the adjacent paving slabs breaks any initial bond which may take place between the said slabs and the exposed surface of the base member 1 and its component elements, thus providing a riding surface for repeated cycles of movement of the slabs.

The function of the device of the present invention in transferring the traffic load from the end of one paving slab to the next paving slab is as follows:

As the traffic load is established adjacent the end of one of the paving slabs, there is established a compression force on the extension 2 which is immediately therebelow. The rigidity and resistance of the base member to bend across the distance equal to the thickness of the compressible element 26 diverts this force into tension on the opposite complementary vertical extension 5, which in turn is securely bonded in the opposite paving slab at its integrally formed horizontal extension 8. As the traffic load moves across the mastic seal 38 and on to the next paving slab, the forces are reversed in complementary function.

While I have shown and described one specific embodiment of the present invention, it will be understood that I do not wish to be limited exactly thereto, since various modifications may be made without departing from the scope of the invention as defined by the appended claims.

I claim:

1. A joint for concrete pavement and the like, comprising a unitary base member adapted to underlie the joint and extend in opposite directions for a substantial distance beneath each slab, a pair of integral upright members carried by said base member so as to extend upwardly in substantial parallelism between the slab sections respectively adjacent each of the end faces of the latter, the upper extremity of each upright member being turned to penetrate into its respectively proximate slab section in a substantially horizontal direction, a compressible element at each of the oppositely extended ends of said base member, a compressible element between said upright members, and a compressible element between each of said upright members and the respectively proximate slab section.
2. A joint for concrete pavement and the like, comprising a unitary base member adapted to underlie the joint and extend in opposite directions for a substantial distance beneath each slab, a pair of integral upright members carried by said base member so as to extend upwardly in substantial parallelism between the slab sections respectively adjacent each of the end faces of the latter, the upper extremity of each upright member being turned to penetrate into its respectively proximate slab section in a substantially horizontal direction, a compressible element between said upright members, a compressible element at each of the oppositely extended ends of said base member, a compressible element between each of said upright members and the respectively proximate slab section, and means for initially holding said base member in position.
3. A joint for concrete pavement and the like, comprising a unitary base member adapted to underlie the joint and extend in opposite directions for a substantial distance beneath each slab, a pair of integral upright members carried by said base member so as to extend upwardly in substantial parallelism between the slab sections respectively adjacent each of the end faces of the latter, the upper extremity of each upright member being turned to penetrate into its respectively proximate slab section in a substantially horizontal direction, a compressible element between said upright members, a compressible element at each of the oppositely extended ends of said base member, a compressible element between each of said upright members and the respectively proximate slab section, and means for holding said last-named compressible elements in position.
4. A joint for concrete pavement and the like, comprising a unitary base member adapted to underlie the joint and extend in opposite directions for a substantial distance beneath each slab, a pair of integral upright members carried by said base member so as to extend upwardly in substantial parallelism between the slab sections respectively adjacent each of the end faces of the latter, the upper extremity of each upright member being turned to penetrate into its respectively proximate slab section in a substantially horizontal direction, a compressible element between said upright members, a compressible element at each of the oppositely extended ends of said base member, and a compressible element between each of said upright members and the respectively proximate slab section, said first-named compressible element extending substantially the entire width of the pavement.
5. A joint for concrete pavement and the like,

comprising a unitary base member adapted to underlie the joint and extend in opposite directions for a substantial distance beneath each slab, a pair of integral upright members carried by said base member so as to extend upwardly in substantial parallelism between the slab sections respectively adjacent each of the end faces of the latter, the upper extremity of each upright member being turned to penetrate into its respectively proximate slab section in a substantially 10

horizontal direction, a compressible element between said upright members, a compressible element at each of the oppositely extended ends of said base member, a compressible element between each of said upright members and the respectively proximate slab section, and a rod carried by at least one of said integral upright members and projecting from either side thereof.

ALAN E. BRICKMAN.
